B. DAVIES.
ORNAMENTATION OF GLASSWARE.

No 18,791.

Patented Dec. 11, 1888.

UNITED STATES PATENT OFFICE.

BENJAMIN DAVIES, OF BROOKLYN, ASSIGNOR TO L. STRAUS & SONS, OF NEW YORK, N. Y.

DESIGN FOR THE ORNAMENTATION OF GLASSWARE.

SPECIFICATION forming part of Design No. 18,791, dated December 11, 1888.

Application filed October 22, 1888. Serial No. 288,844. Term of patent 7 years.

To all whom it may concern:

Be it known that I, BENJAMIN DAVIES, a subject of the Queen of Great Britain, and a resident of Brooklyn, in the county of Kings and State of New York, have invented and produced a new and original Design for the Ornamentation of Glass and other Ware; and I do hereby declare the following to be a full, clear, and exact description of said invention, reference being had to the accompanying photographs, and to the letters or figures of reference marked thereon, which form a part of this specification.

I have shown my design embodied in three separate articles—viz., a large dish, a goblet, and a small dish. (Shown, respectively, in Figures 1, 2, and 3.)

In Fig. 1 the design appears the clearest, and is duplicated on both sides of the central vertical line of truncated pyramids *a*. In Fig. 2 the design is shown both above and below the horizontal line of truncated pyramids *a*; but the figures below are smaller than those above, due to the shape of the goblet. In Fig. 3 the design is shown only outside of the circular line of truncated pyramids *a*.

The leading feature of my design consists in a dish or other ware having a surface ornamentation of three series of squares, two of

which series are subdivided by curved lines 30 into angular figures and small pyramids. The surface ornamentation is of two kinds, the lines 1 being straight and at right angles to each other, or as nearly so as the shape of the article will permit, while the lines 2 are curved, 35 as shown. The lines 1 present a series of squares which at *a* are truncated pyramids, having a checkered surface showing a series of small cross-cuts or depressions. The squares next to the pyramids *a* are divided by the 40 curved lines 2 into three angular figures, *b*, *b* and *c*, the figures *b* being plain-faced, while the top of figure *c* has a rosette of small radial cuts or depressions. The third series of squares are divided by the curved lines 2 into 45 four small pyramids, *d*, having checkered surfaces similar to pyramids *a*.

What I claim is—

The design for the ornamentation of glass and other ware, substantially as herein described and shown. 50

In testimony whereof I affix my signature in presence of two subscribing witnesses.

BENJAMIN DAVIES.
